DEVICE FOR CONTROLLING A MONITORING RELAY

Jacques Fossé, Argenteuil, and Louis Déprez, Paris, France, assignors to North American Philips Company, Inc., New York, N.Y., a corporation of Delaware

Filed Aug. 13, 1962, Ser. No. 216,427

10 Claims. (Cl. 317—146)

The invention relates to a device for controlling a monitoring relay by means of a monitoring signal.

Such a monitoring relay is employed inter alia in a safety system for railways, for example, for the electronic indication of the passage of a train at a given point, for controlling level-crossing signals, barriers and the like. In such systems high requirements are made on reliability and safety so that, if a disturbance occurs somewhere in the system, for example, a failure in the energizing circuit of a relay or if the supply voltage drops out, accidents will not occur. In order to provide fail-safe operation, use is commonly made of a "rest" current. This means that the monitoring relay is normally energized under the control of a monitoring signal and is temporarily de-energized at the passage of a train which temporarily interrupts the monitoring signal. If the train has a high speed, this interruption will take only a very short time, so that the relay remains de-energized only for a short time. It is, however, very important that both the relay and the relay-controlled further safety arrangement should respond with certainty to the interruption of the monitoring signal of the relay, even if this interruption takes only a very short time.

The invention provides a reliable solution to this problem. In accordance with the invention, the monitoring signal is supplied to the relay via a gate circuit which is normally conducting under the control of a voltage picked up between the gate and the relay. In the deenergized or rest position of the relay, an energizing circuit is closed via a delay circuit independently of the condition of said gate circuit.

The invention will be described more fully with reference to the embodiment shown in the figure.

The drawing shows diagrammatically part of a mainly electronic monitoring circuit for the indication of the passage of a train. In the proximity of the rails A1, A2 there is arranged a continuously running oscillator B, which supplies normally a monitoring signal to an input terminal 1 of the And-gate P₁. The monitor signal appears at the output terminal 2 of And-gate P₁ and is coupled to one input terminal 3 of the Or-gate P₂. Output terminal 4 of Or-gate P₂ supplies the monitor signal to the input of the amplifier C, which amplifies and rectifies the signal. The output of amplifier C is connected to the input terminal 8 of a relay R. The monitoring relay R is therefore normally energized under the action of the direct output voltage of the amplifier device C. This direct voltage may be supplied via a feedback path T to a second input terminal 5 of And-gate P₁ to control the condition thereof. The direct voltage controls the gate P₁ so that this gate is normally conducting or open when the direct voltage is present at terminal 5 and thereby passes the monitoring signal of the oscillator B. Oscillator B may be of the general type disclosed in U.S. Patent 2,105,930, which issued January 18, 1938. The And-gate P₁ may be chosen from among the circuits disclosed at pages 400, 436 and 437 of the text book "Pulse and Digital Circuits" by Millman and Taub (McGraw-Hill Book Co., 1956). Suitable circuits for Or-gate P₂ are shown at page 396 of the Millman and Taub book or at pages 642 and 643 of "Waveforms," vol. 19 of the Radiation Laboratory series edited by Britton Chance et al. (McGraw-Hill Book Co., 1949). Amplifier C may

2

be chosen from among the amplifier circuits described in chapters 6 and 7 of the text book "Radio Engineering" by F. E. Terman, third edition (McGraw-Hill Book Co., 1947).

The oscillator B is arranged so that at the passage of a train, given parts thereof, for example, the flanges of the wheels, pass closely by the tuned circuit of the oscillator, which is thus damped or detuned, or at any rate is acted upon so that the signal is not passed by the device C and the direct output voltage at the point 6 disappears. Consequently, the gate P₁ is closed so that, if the monitoring signal of the oscillator should immediately thereafter reappear, the gate P₁ can no longer pass this signal and the relay R must remain de-energized.

Via contacts r1 of the relay R, a warning signal is supplied to a further safety arrangement (not shown), which subsequently carries out given control-operations, for example, the closure of barriers, the transition of semaphores to "danger" and the like.

Moreover, in the de-energized state of the relay R, there is closed, via the break contact r2 thereof, or of a further relay, an auxiliary energizing circuit for the relay R from the supply source V. The auxiliary voltage is supplied from the source V to the relay R via contact r2, the delay device D, the gate P₂ and the amplifier C. The supply source V may be an alternating current source, in which case the delay device D may be an artificial line of the type shown at page 291 of the aforementioned "Pulse and Digital Circuits" or a direct voltage source, the delay device comprising for example an oscillator which is made operative with a given delay. The delayed auxiliary signal is coupled from the output of delay element D to a second input terminal 7 of Or-gate P₂, through the gate to output terminal 4 and then to the input of amplifier C. Under the action of the signal supplied to the amplifier C, a direct voltage is produced at the output of said amplifier so that the relay R is re-energized and the gate P₁ is again rendered conducting. After the contact r2 is re-opened, the relay R remains energized under the control of the monitoring signal supplied by the oscillator B, and the initial state is restored. However, if the oscillator monitoring signal had not yet returned in the meantime, the opening of the auxiliary energizing circuit by means of the contact r2 would cause a de-energization of the relay R, after which the process is repeated until the oscillator monitoring signal reappears.

As stated above, the relay R, after its de-energization, cannot be immediately re-energized owing to the presence of the delay circuit D. The delay time thereof is such that the relay must always remain de-energized for a given time which is sufficient to insure that the circuits which must respond to the de-energization of the relay R have a sufficient time to respond.

In the embodiment described above use is made of alternating current signals for controlling the relay R. It is also within the scope of the invention to employ direct current signals instead of A.C. signals to control the relay. The use of alternating current, however, has various advantages. For example, an electronic train detector in the form of the oscillator B may be employed to which no moving parts are connected. Known train detectors operating with switches controlled mechanically by the train have the disadvantage that in spite of a careful construction damage thereto frequently occurs in practice.

65 What is claimed is:

1. Signal control apparatus comprising means for generating a monitor signal in response to an external condition, a load device having an input terminal for a control signal, said load device having first and second operative states determined by the condition of said control signal at its input terminal, gate circuit means having input means and output means and connected between

said signal generating means and said load device input terminal for controlling the passage of said monitor signal from said signal generating means to said load device, circuit means responsive to the presence of said monitor signal at said output means for supplying a control signal to said gate circuit input means thereby to maintain said gate circuit in its open condition, said monitor signal further controlling said load device into said first state, and means responsive to the state of said load device for supplying a delayed control signal to said gate circuit input means when said load device is in said second state.

2. Apparatus as described in claim 1 further comprising means for coupling said delayed control signal to said load device input terminal thereby to return said load device to said first state.

3. Signal control apparatus comprising means responsive to an external condition for generating a monitor signal, a load device having a first normally energized state and a second state and including an input terminal for a control signal which controls the state thereof, gate circuit means having input means and output means, means for coupling said monitor signal from said signal generating means to said gate circuit input means, circuit means for coupling said gate circuit output means to said load device input terminal, said circuit means further comprising means for supplying a control signal to said gate circuit input means for controlling the condition of said gate circuit as a function of said monitor signal, delay means having an input and an output, means responsive to the state of said load device for supplying a signal to the input of said delay means when said load device is in said second state, and means coupling a delayed signal from the output of said delay means to said gate circuit input means thereby to open said gate circuit.

4. Signal control apparatus comprising means for selectively generating a monitor signal in response to an external manifestation, a load device having an input terminal for a control signal, said load device being responsive to a control signal applied thereto for selectively controlling said load device into a first and second state, gate circuit means having first and second input terminals and an output terminal, means for coupling said monitor signal from said signal generating means to said gate circuit first input terminal, circuit means for coupling said gate circuit output terminal to said load device input terminal, said circuit means further comprising means for supplying a control signal to said gate circuit second input terminal for controlling the passage of said monitor signal through said gate circuit means, delay means having an input and an output, means responsive to the state of said load device for supplying a signal to the input of said delay means when said load device is in said second state, said circuit means further comprising means coupling the output of said delay means to said load device input and to said gate circuit second input terminal to supply thereto a delayed control signal, said delayed control signal being operative to open said gate circuit and also to return said load device to said first state.

5. Signal control apparatus comprising means for selectively generating a monitor signal determined by an external condition, a load device having an input terminal for a control signal, said load device having a first normally energized state and a second state corresponding to the presence and absence of a control signal at said input terminal, respectively, gate circuit means having first and second input terminals and an output terminal, means for coupling said monitor signal from said signal generating means to said gate circuit first input terminal, circuit means for coupling said gate circuit output terminal to said load device input terminal and to said gate circuit second input terminal whereby the presence of said monitor signal at said output terminal maintains said gate circuit open and said load device in said first normally energized state, and means responsive to the state

of said load device for supplying a delayed control signal to said gate circuit second input terminal and to said load device input terminal when said load device is in said second state, said delayed control signal being operative to open said gate circuit and also to return said load device to said first state.

6. Apparatus as described in claim 5 wherein said circuit means further comprises an OR gate having first and second input terminals and an output terminal, means connecting said OR gate first input terminal to said gate circuit output terminal, means coupling said delayed control signal to said OR gate second input terminal, and means coupling said OR gate output terminal to said load device input terminal and to said gate circuit second input terminal.

7. A train control system for a section of railway track, comprising means positioned along said track in electro-responsive coupling relationship with a passing train for producing a monitor signal, a load device which is selectively operable between first and second states in response to a control signal applied thereto, a gating device having input means and output means, means connecting said gating device between said signal producing means and said load device so as to effectively control the passage of said monitor signal to said load device, means coupled to said gating device output means for supplying a control signal to said gating device input means to control the condition of said gating device as a function of said monitor signal, said signal producing means being responsive to a passing train to cause a change in the monitor signal produced thereby to actuate said control signal supplying means to close said gating device and change said load device from said first to said second state, and means responsive to the state of said load device for supplying a delayed control signal to said gating device input means in the second state of said load device thereby to open said gating device to said monitor signal.

8. Apparatus for detecting the presence of a train in a given section of railway track comprising, means located near said track and responsive to a passing train for producing a monitor signal having first and second electrical characteristics determined by the absence and presence, respectively, of a train in said given track section, output means responsive to said monitor signal and having first and second operative states corresponding to said first and second characteristics of said monitor signal, respectively, gating means connected between said signal producing means and said output means for effectively controlling the passage of said monitor signal from said signal producing means to said output means, means connected to the output of said gating means for supplying a control signal to said gating means as a function of the monitor signal thereat, said output means and said control signal supplying means being responsive to said monitor signal second characteristic to change over said output means from said first state to said second state and to close said gating means, respectively, means responsive to the state of said output means for applying a delayed control signal to said gating means in the second state of said output means and independently of said gating means thereby to open said gating means.

9. Apparatus as described in claim 8 further comprising means for coupling said delayed control signal to said output means thereby to cause said output means to change over from said second state to said first state.

10. Apparatus for detecting the presence of a train in a given section of railway track comprising, oscillation means located near said track and responsive to a passing train for producing an oscillation signal having first and second oscillation conditions determined by the absence and presence, respectively, of a train in said given track section, a load device responsive to a control signal and having a first normally energized state corre-

sponding to said first oscillation condition and a second state corresponding to said second oscillation condition, a switching device having input means connected to the output of said oscillation means and including output means for said oscillation signal, circuit means interconnecting said switching device output means and input means, said circuit means including means responsive to said oscillation signal at said output means for supplying a control signal to said load device and to said switching device to control the condition thereof, said circuit means being responsive to said first oscillation condition at said switching device output means to control said switching device into a closed condition and said load device into said first state and being responsive to said second oscillation condition at said output means to control said load device into said second state and said switching device

into an open condition, and means responsive to the state of said load device for applying a delayed control signal to said switching device input means independently of said switching device when said load device is in said second state, thereby to close said switching device for the passage of said oscillation signal therethrough.
